G. LANE,

LIFTING JACK.

APPLICATION FILED JULY 11, 1918

1,320,245.

Patented Oct. 28, 1919.

Inventor:

George Lane,
by Spear, Muddleton & Macdonald Spear
Atlys.

UNITED STATES PATENT OFFICE.

GEORGE LANE, OF POUGHKEEPSIE, NEW YORK, ASSIGNOR TO LANE BROS. CO., OF POUGHKEEPSIE, NEW YORK, A JOINT STOCK ASSOCIATION OF NEW YORK.

LIFTING-JACK.

1,320,245.

Specification of Letters Patent.

Patented Oct. 28, 1919.

Continuation of application Serial No. 114,426, filed August 11, 1916. This application filed July 11, 1918.
Serial No. 244,464.

To all whom it may concern:

Be it known that I, GEORGE LANE, a citizen of the United States, residing at Poughkeepsie, New York, have invented certain new and useful Improvements in Lifting-Jacks, of which the following is a specification, this application being a continuation of an application filed by me on the 11th day of August, 1916, Serial Number 114,426.

10 My invention relates to improvements in lifting jacks adapted more especially for use in connection with motor vehicles, and is designed as an improvement upon the jack disclosed in Letters Patent #1,181,395, granted to me on the 2nd of May 1916.

In devising the present invention I have aimed to simplify the construction by eliminating certain parts; to secure a positive motion of the contact pin or device in both 20 directions by the operator instead of a spring action one way; to eliminate the constant urging of the handle backward by the spring and the consequent tendency of its getting into an intermediate position, and 25 further to provide a construction which will compensate for commercial variations and render unnecessary alterations in the jack.

A still further object is to provide a construction with an extremely simple form of 30 folding handle which will be of maximum strength and rigidity when in use, and in which the reversal of the jack may be effected by a push or pull upon the outer end of the handle bar.

35 With these and other objects in view the invention includes the novel features of construction and arrangement and combination of parts hereinafter described, my said invention being defined by the appended 40 claims.

An embodiment of the invention is illustrated in the accompanying drawing, in which,

Figure 1 is a sectional elevation of a sufficient portion of a jack to illustrate my invention.

Fig. 2 is a cross section through the actuating lever with the handle bar in place.

Fig. 3 is a longitudinal section through 50 the handle bar, and,

Fig. 4 is a plan view of the same.

Referring by reference characters to these drawings, the standard 2, lifting bar 3 and

lifting and retaining dogs 4 and 5 are shown as constructed and arranged to be operated 55 as in my aforesaid patent, the lifting and retaining dogs being connected by the springs 14 and 13 with the bell crank levers 12 and 11 mounted alongside the actuating lever 6, and having their contact portions 60 pressed toward each other by a common spring C.

Actuating lever 6 is provided with a socket to receive a handle bar of material length to enable the jack to be placed in 65 position without crawling under the car, which handle is made folding to enable it to be conveniently placed in the tool box and is retained in the socket by a spring 70 dog 19.

To effect the reversal of the jack I provide a shiftable contact pin or controller b which is designed in one position (shown in full lines in Fig. 1) to contact with the bell crank levers alternately as the actuating 75 lever is operated, and thus effect the lowering of the lifting bar, while in another position the pin or contact portion lies beyond the range of said bell crank levers, as shown in dotted lines at b' in Fig. 1, 80 whereby the pawls 4 and 5 operate to effect the step by step raising of the lifting bar.

This pin or controller is carried on a thin strip of sheet metal 8^x slidably carried on the side of the forward portion handle bar 85 7^x. The aggregate thickness of the end of the handle bar and the metal strip is such as to enable it to be inserted in the socket of the actuating lever, as shown in Fig. 2. The thin or controller actuating strip is held to 90 the side of the handle bar by the controlling pin at its front end which passes through an elongated slot x in the front end of the handle bar, and at its rear end by a rivet 20 which passes through a slot x' in the 95 handle bar. The handle bar is composed of two sections 7^x and 7^y pivotally connected together by the rivet 20 above referred to, and to lock them together in front of rivet 20, a pin 21 is adapted to pass through the slot x'' 100 in the handle bar portion 7^x, and an alining recess in the section 7^y.

A chain or other flexible connection may be provided for attaching the pin 21 to the handle bar to prevent loss of the pin when 105 removed for folding.

With the handle bar in place as shown in Fig. 1 a pull upon the handle bar section 7^y moves the pin or controller to its outermost position shown in Fig. 1 in dotted lines and sets the jack for raising, while a push upon said section 7^y moves the pin or controller forward into the position shown in full lines Fig. 1 and sets the jack for lowering.

Having thus described my invention, what I claim is:—

1. A jack comprising a standard, a lifting bar, lifting and retaining pawls, a lever mounted in the standard having a socket for receiving an operating bar, devices carried by the standard for controlling the operation of the pawls, a handle bar having an end adapted to be held in the socket, and a shiftable member carried by said operating

bar having a controller to act directly upon said devices movable into and out of actuating position in reference to said devices.

2. A jack comprising a standard, a lifting bar, lifting and retaining pawls, an actuating lever mounted in the standard having a socket for receiving an operating bar, devices carried by the standard for controlling the operation of the pawls, an operating bar having an end adapted to be held in the socket, said operating bar comprising two members connected together to have relative sliding movement, a shiftable member carried by the innermost member and connected to be operated by the outermost member and

a controller connected to said shiftable member to act directly upon said devices.

3. A jack comprising a standard, lifting bar, lifting and retaining pawls, an actuating lever mounted in the standard having a socket for receiving an operating bar, devices carried by the standard for controlling the operation of the pawls, an operating bar having an end adapted to be held in the socket, said operating bar comprising two members pivotally connected together to have relative sliding movement when in alinement with each other, a shiftable member carried by the innermost member and connected to be operated by the outermost member, a controller connected to said shiftable member and releasable means for locking said members of the operating bar in alinement.

4. A jack comprising a standard, a lifting bar, lifting and retaining pawls, a lever mounted in the standard having a socket for receiving an operating bar, devices carried by the standard for controlling the operation of the pawls, a handle bar having an end adapted to be held in the socket, a thin flat sheet metal bar slidably held to one side of said handle bar, and a laterally extending controller carried by said sheet metal bar and acting directly upon the said devices.

In testimony whereof, I affix my signature.

GEORGE LANE.
